ICE SHAVER

Kenneth R. Harmon, Norfolk, Va.

Application May 24, 1932, Serial No. 613,304

7 Claims. (Cl. 83—62)

This invention aims to provide an ice-shaving machine characterized by the following features: ready access to the shaving blades, through the instrumentality of a movably mounted delivery chute: a delivery chute which will open automatically and release the shaved ice, when clogged by shaved ice: a support for the rotary cutter, which is mounted in one side plate of the casing only: improved bearing means for the shaft of the rotary cutter: novel means for lubricating the shaft of the rotary cutter, without contaminating the shaved ice by lubricating oil: other objects being to improve generally, and to enhance the utility of devices of that type to which the present invention appertains.

A preferred form has been shown, but is to be regarded as an illustrative material embodiment of the invention only, since a mechanic, working within the scope of what is claimed, may depart from the structure shown, without placing the utility of the invention in jeopardy, or departing from the spirit of the invention.

In the accompanying drawings:

Fig. 1 shows in elevation, an ice shaver constructed in accordance with the invention;

Fig. 2 is an elevation wherein the device is viewed at right angles to the showing of Fig. 1;

Fig. 3 is a section on the line 3—3 of Fig. 2;

Fig. 4 is a section on the line 4—4 of Fig. 3;

Fig. 5 is a section on the line 5—5 of Fig. 2.

The device forming the subject matter of this application is made of metal. It includes a casing, which, as a whole, is marked by the letter C.

The casing C comprises a first side plate 1 and a second side plate 2, having outstanding marginal flanges 3 connected by securing elements 4, such as rivets.

The first side plate 1 has an outstanding angle bracket 5, by which the casing C is supported. The first side plate 1 is provided at its center with an outwardly projecting tubular bearing 6 having a longitudinal bore 7. In the inner end of the bearing 6 and in the side plate 1 there is a recess 8.

The bottom part of the bearing 6 is connected to the side plate 1 by an enlargement 9, in which there is an oil pocket 10, provided on its inner side with a vertical wall 11. The oil pocket 10 forms the bottom part of the recess 8. The upper end of a downwardly inclined pipe or drain conduit 12 is connected to the enlargement 9 and communicates with the oil pocket 10. The outer end of the pipe 12 is mounted in the vertical flange of the angle bracket 5 on the side plate 1.

A bushing 14, which may be made of bronze

or any other suitable material, is secured in the bore 7 of the bearing 6 and extends inwardly to the base of the recess 8. A bushing 15, made of bronze or any other suitable material, is secured in the outer end of the bore 7 of the bearing 6, and has a laterally enlarged head 16 engaged with the outer end of the bearing 6. On the head 16 of the bushing 15, a cap 17 is threaded, or held otherwise, removably.

A shaft 18 is journaled for rotation in the bushings 14 and 15. The inner end of the shaft 18 is tapered, as shown at 19. A nut 20 is threaded on the outer end of the part 19 and is housed in an offset 21 on the second side plate 2. The outer end of the shaft 18 is reduced, as shown at 22, and on the reduced end of the shaft is threaded an inner nut 23 and a lock nut 24. A lock washer 25 is interposed between the nuts 23 and 24. The nuts 23 and 24 and the lock washer 25 are housed within the cap 17. The cap 17 may be taken off to get at the nuts 23 and 24.

A rotor 26, in the form of a disk, is disposed in the casing C, and has a hub 27 held on the tapered end 19 of the shaft 18 by the nut 20. The inner end of the hub 27 of the rotor 26 abuts against the shoulder in the bearing 6, formed by the base of the recess 8. The hub 27 of the rotor 26, and the nuts 23 and 24, hold the shaft 18 against moving endwise, and keep the rotor 26 spaced from the side plates 1 and 2 of the casing C.

There are oil holes 28 on the upper side of the bearing 6, these oil holes communicating with reduced oil holes 29 in the bushings 14 and 15. There is a space 30 between the inner ends of the bushings 14 and 15. The oil holes 28, of course, are typical of any suitable lubricating instrumentality. The oil introduced into the holes 28 passes through the holes 29 and lubricates the shaft 18. The space 30 between the inner ends of the bushings 14 and 15 constitutes an oil reservoir. The oil that works toward the hub 27 of the rotor 26 finds its way into the oil pocket 10, because the inner end of the hub 27 and the shoulder at the base of the recess 8 are directly above the oil pocket 10. From the oil pocket 10, the oil drip runs away through the pipe 12. It will be seen that surplus oil is intercepted by the pocket 10, before the oil can find its way within the casing C and contaminate the ice which is being shaved.

The rotor 26 has a peripheral gear 31 meshing with a pinion 32 secured to a shaft 33 journaled in an offset housing 34, to which is se-

cured, externally of the casing C, an electric motor 35, of which the shaft 33 forms a part. Any other means may be supplied for imparting rotation to the rotor 26.

The means whereby the ice is cut immediately, may be of any desired kind. If preferred, openings 36 may be formed in the rotor 26, and to one edge of each opening is secured a knife 37, the knives having transverse slots 38, receiving securing elements 39 which attach the knives to the rotor 26, so that the knives can be adjusted in and out with respect to the second side plate 1, as Fig. 3 will show. The knives 37 are disposed at an acute angle to the rotor 26.

18 An ice hopper 40 is formed integrally with the side plate 1 of the casing C and with the bearing 6. The ice hopper 40 is open at its upper end, and on its inner side, throughout its length, it opens through the side plate 1, against the rotor 26. The bottom of the ice hopper 40 slopes downwardly and inwardly, as shown in Fig. 1, so that the ice in the hopper will be held by gravity against the rotor 26 in the path of the knives 37, as the ice tends to slide downwardly along the bottom of the hopper.

Opposite to the hopper 40, the side plate 2 of the casing C is provided with an opening 41, covered by a substantially vertical, trough-shaped outlet chute 42 which is open at its upper and lower ends. The chute 42 extends downwardly a little way beyond the lower edge of the casing C, and the side plate 1 of the casing has a corresponding extension 43, shown in Fig. 1, to cooperate with the downwardly extended lower part of the chute 42.

35 By means of hinges 44, the chute 42 is connected, along its inner edge, with the side plate 2 of the casing C, to swing horizontally. The outer edge of the chute 42 is held against the side plate 2, in closed relation to the opening 41, by a releasable latch, which may be of any desired construction. The releasable latch may comprise outstanding jaws 45 on the side plate 2, a finger 46, rigidly connected to the chute 42, being received between the fingers 46. The jaws 45 are stiff enough to hold the outlet chute 42 closed under all ordinary working conditions, but the jaws can yield, to release the finger 46, and permit the chute 42 to open, under abnormal conditions, which will be described hereinafter.

50 One of the main advantages of the device is that the shaft 18 is carried entirely by the side plate 1, and is not supported in any way in the side plate 2. This construction facilitates assembly and repair and has many other advantages which will be appreciated readily by practical users of the article.

55 As to general operation, the ice is cast into the hopper 40, and the inclined bottom of the hopper carries the ice against one side of the rotor 26. The rotor 26 is turned by means of the gear 31, the pinion 32, the shaft 33, and the motor 35 or any other instrumentality adapted for the purpose in view. As the rotor 26 turns, the knives 37 shave the ice, the ice passes through the openings 36 of the rotor 26, into the outlet chute 42, the shaved ice dropping out of the lower end of the chute 42.

70 There are several reasons for mounting the outlet chute 42 hingedly, as shown at 44. One reason for doing this is to give ready access to the knives 37, in order that the knives may be adjusted, cleaned, or taken off for sharpening or renewal. Another reason for hingedly mount-

80 ing the ice chute 42, and holding it closed releasably by means of the latch mechanism shown at 45 and 46, is that sometimes the ice chute or outlet chute 42 will clog up with ice, as the ice accumulates below the lower end of the chute. As soon as there is an undesirable jam or pressure within the chute 42, the chute will open on its hinges 44, because of the resilient hold of the jaws 45 on the finger 46 of the chute.

85 The bearing shown in Fig. 5 affords a substantial support for the shaft 18, even though the shaft is mounted only in the bearing 6, and not in the side plate 2.

90 The oil supplied from the holes 28 and 29, if it works inwardly, past the bushing 14, will drip down into the oil pocket 10 and be carried away by the pipe 12, there being no fouling of the shaved ice in the casing C, by the oil drip.

95 Having thus described the invention, what is claimed is:

100 1. An ice-shaver comprising a casing having an inlet for the ice to be shaved, and an outlet for the shaved ice, the casing comprising oppositely-disposed first and second side plates, the first side plate having an outwardly projecting tubular bearing provided with a bore, the bearing being supplied at its inner end with a recess of larger diameter than the bore, a bushing in the outer end of the bore and provided with a laterally-enlarged head engaging the outer end of the bearing, a shaft journaled in the bushing, a securing device removably mounted on the outer end of the shaft and engaging the head of the bushing, a cap covering the securing device and removably mounted on the head of the bushing, a rotor in the casing and including a hub secured to the inner end of the shaft and engaging the bearing, within the 115 recess, the hub and the securing device constituting means for holding the shaft against endwise movement, but for rotation, in the bearing, the inner end of the shaft being spaced from the second side plate, ice-shaving means carried 120 by the rotor, and means for rotating the rotor.

125 2. An ice-shaver comprising a casing having an inlet for the ice to be shaved, ice-shaving means within the casing, an outlet chute for shaved ice, means for hinging the outlet chute 130 upon the casing, and latch mechanism connecting the outlet chute with the casing, to hold the outlet chute closed with respect to the casing, said mechanism comprising interengaged parts which are automatically releasable, to permit the outlet chute to open with respect to the casing, when there is abnormal pressure of shaved ice within the outlet chute.

135 3. An ice-shaver comprising a casing having an inlet for the ice to be shaved, and an outlet for the shaved ice, an outstanding bracket carried by the casing and constituting means for supporting the casing, a bearing on the casing, a shaft journaled in the bearing, a rotor in the casing and carried by the shaft, a shaving device on the rotor and located within the casing, reservoir means for intercepting foreign material moving along the shaft, said reservoir means being located within the casing, at the extreme 140 end of the bearing, to intercept foreign material before the foreign material finds its way into the casing, to contaminate the ice, a pipe external to the casing and connected detachably to the reservoir means, the pipe constituting an outlet 145 for the foreign material in the reservoir means, 150

- and the pipe being supported in the said bracket. 4. An ice-shaver comprising a casing having an inlet for the ice to be shaved, and an outlet for the shaved ice, a bearing on the casing, a shaft journaled in the bearing, a rotor in the casing and carried by the shaft, a shaving device on the rotor, and the casing being provided with a pocket for foreign material moving along the shaft, the pocket being located within the casing and below the shaft, at the extreme inner end of the bearing, the upper portion of the pocket being in open communication with the interior of the casing, to admit air into the pocket, the pocket constituting means for intercepting foreign material before the foreign material enters the casing and contaminates the ice, and a laterally extended drainage conduit of considerable length, communicating with the pocket. 5. An ice-shaver comprising a casing having an inlet for the ice to be shaved, and an outlet for the shaved ice, a bearing on the casing, a shaft journaled in the bearing, a rotor in the casing and carried by the shaft, a shaving device on the rotor, reservoir means located within the casing and at the extreme inner end of the bearing for intercepting foreign material moving along the shaft, before the foreign material finds its way into the casing, to contaminate the ice, and a conduit connected to the reservoir means and forming an outlet for the reservoir means. 6. An ice-shaver comprising a casing having an inlet for the ice to be shaved, and an outlet for the shaved ice, a bearing on the casing, the bearing being provided with a bore, and there being an enlarged recess at the inner end of the bore, the bearing having a pocket located in the casing at the inner end of the recess, the pocket forming the bottom of the recess, the pocket having an upwardly extended wall spaced from the inner end of the recess, a shaft journaled in the bearing, a rotor disposed in the casing and including a hub extended into the recess and secured to the shaft, the hub extending outwardly beyond the said wall of the pocket, so as to intercept foreign material moving along the shaft and direct the foreign material into the pocket, before the foreign material can enter the casing and contaminate the ice in the casing, means for draining the pocket, and ice-shaving means on the rotor. 7. An ice shaver comprising a casing having an inlet for the ice to be shaved, ice-shaving means within the casing, an outlet chute for shaved ice, means for mounting the outlet chute hingedly at one side on the casing, and releasable mechanism for holding the opposite side of the outlet chute in closed position with respect to the casing, said mechanism being releasable under pressure of accumulated shaved ice in the outlet chute, to permit the outlet chute to open with respect to the casing. 35 110 40 115 45 120 50 125 55 130 60 135 65 140 70 145 75 150
